SPECTACLE FRAME

Albert L. Anderson, Minneapolis, Minn., assignor
to Precision-Cosmet Company, Inc., Minneapolis, Minn., a corporation of Minnesota

Application August 19, 1948, Serial No. 148,192

Term of patent 14 years

(Cl. D57—1)

To all whom it may concern:

Be it known that I, Albert L. Anderson, a citizen of the United States, residing at Minneapolis, in the county of Hennepin and State of Minnesota, have invented a new, original, and ornamental Design for a Spectacle Frame, and of which the following is a description, reference being had to the accompanying drawing, forming part thereof.

Figure 1 is a front elevational view of a spectacle frame, showing my new design;

Figure 2 is a side elevational view thereof;

Figure 3 is a top plan view with one of the temples in a folded position;

Figure 4 is an enlarged typical sectional view taken on the line 4—4 of Fig. 2; and

Figure 5 is an enlarged typical portion of the ornamental surface shown in Figs. 1-3, inclusive.

I claim:

The ornamental design for a spectacle frame, as shown.

ALBERT L. ANDERSON.
